UNITED STATES PATENT OFFICE.

MATTHEW HOWARD REED, OF PITTSBURG, PENNSYLVANIA.

CONCRETE-MIXER.

939,629.

Specification of Letters Patent.

Patented Nov. 9, 1909.

Application filed February 10, 1909. Serial No. 477,164.

To all whom it may concern:

Be it known that I, MATTHEW HOWARD REED, a citizen of the United States, residing at Pittsburg, in the county of Allegheny and State of Pennsylvania, have invented certain new and useful Improvements in Concrete-Mixers, of which the following is a specification, reference being had therein to the accompanying drawing.

10 My invention consists of an improvement in concrete mixers and refers particularly to the mechanism for actuating the charging blades or the covering gate for the delivering chute.

15 The object of the invention is to provide means for operating the blades or gate and also for holding the blades in mixing or discharging position and for holding the gate open or closed and providing for operating either from either end of the mixer drum, by means of lever and spring mechanism, as shall be more fully hereinafter described.

20 Referring to the drawings:—Figure 1 is a view in front elevation of the mixer drum and portions of its supporting and rotating mechanism. Fig. 2 is a view of the drum from the back. Fig. 3 is a horizontal section on the line III. III. of Fig. 1. Fig. 4 is a vertical sectional view on the line IV. IV. of Fig. 1 partly broken away. Figs. 5 and 6 are detail views showing modifications. Fig. 7 is a view similar to Fig. 1, but showing a modified construction of spring. Fig. 8 is a view of Fig. 7 from the other end, the levers being shown in both positions. Fig. 9 is a vertical sectional view on the line IX. IX. of Fig. 7 but showing the mixing blades thrown out to contact with the drum for discharging, and located at top and bottom of the drum. Fig. 10 is a similar view showing the blades at the same locations but in the mixing position.

25 In the drawings, 2 represents the drum of cylindrical form, having a rear annular receiving chamber 3 between a back annular flange 4 and a rear partition 5. Partition 5 is provided with a centrally arranged inlet opening 6 and the shell between partition 5 and flange 4 has any suitable lifting mechanism, not shown, such as those shown in my prior application filed September 28th, 1908, Ser. No. 455101.

30 The front wall 7 of the drum is provided with a centrally arranged outlet opening defined by the delivery chute 8 which in the position shown in Fig. 1 slopes downwardly

and terminates in upper horizontal edges 9, and opens into the interior or mixing compartment of the drum.

35 The delivery chute is provided with a closing door or cover 10 entirely within the mixing chamber and immediately behind the front wall 7, mounted on a hinge rod 11 pivotally carried in suitable bearings in the front and back wall respectively. Rod 11 is provided, at the front with an operating lever 12 and at the back with a similar operating lever 13 secured in any suitable manner, and these levers are so located that when the gate is thrown open, the levers will 40 occupy the positions in dotted lines in Figs. 1 and 2, the rear lever 13 extending across the opening 6. By this construction the gate may be operated by the lever at either end and the position of the rear lever will always 45 indicate to the workman whether the gate is open or closed. When open, the material will pass through the chute, and when closed will be deflected away therefrom to other portions of the mixer.

50 For the purpose of positively holding the gate in either open or closed position, I provide a tension spring 14 secured at one end by any suitable attachment, as a bolt 15, preferably provided with a nut by which 55 it may be adjusted in its bearing to tighten or loosen the spring. 16 is a link connecting spring 14 with lever 12, of arc shape as shown, so that when the lever is thrown downwardly into the position shown in dotted lines for opening the gate, the arc-shaped link 16 will reach around the end of shaft 11 without interference, as clearly shown.

55 The point of attachment of link 16 with lever 12, is designed to pass beyond the dead center alignment with shaft 11 sufficiently far to insure a pull of the spring on the other side to positively hold the gate raised, as will be readily understood, while the normal tension of the spring in the closed position of 60 the gate, tends to maintain it closed. By this construction it will be seen that the gate may be open or closed from either end by operating either lever 12 or 13, and will remain in either position against accidental 65 shift or motion.

70 Ordinarily, the gate lies down upon the top edges of chute 8 as indicated in the principal figures of the drawings.

75 In Fig. 5 I have shown a construction in which the cover 10 fits within the edge of chute 8 as shown, and rests upon an inner

supporting ledge or flange 17 which may be conveniently made of angle shape and riveted to the inner side of the chute wall.

In Fig. 6 I illustrate the same construction and also a lateral supplemental chute extension 18 adapted to be set at varying heights upwardly above the main side wall 8 of the chute, for the purpose of partially cutting off the entrance opening from the interior of the drum into the chute. This arrangement is of advantage in easily and conveniently controlling the flow of the material at each revolution to any desired amount independent of the opening and closing gate and by employing slotted holes and securing bolts the range of movement or adjustment of the extension may be accurately limited as desired.

The advantages of the invention will be readily appreciated by all those familiar with this class of mechanism. The operation will be readily understood, the mixing drum being rotated with the door closed until it is desired to discharge, whereupon it may be thrown open until the contents have been discharged into a barrow or other suitable receiving vessel, when the gate may be again closed and the drum re-filled. The location of the handle 13 at the front end so as to indicate the condition of the door is of great advantage in addition to the facility of operation from either end.

Figs. 7, 8, 9 and 10 show a drum of similar construction but with a discharge arrangement consisting of a stationary chute, not revolving with the drum but arranged to discharge the material which is dropped on it to the outside of the drum, the material being all or partially lifted by the discharging blades when they are thrown into discharging position. In these figures, 19 is the delivery chute, preferably supported by timber 19' of a platform or other mounting. 20 is the discharging blade at each side, mounted on shaft 21 with suitable bearings in mixer shell.

Shaft 21 is provided with a lever 22 at the discharging end of the drum and lever 23 at charging end and with a band or leaf tension spring 24, preferably attached to lever 22 and to a suitable terminal attachment as a bolt 25 mounted in bracket 26, with an adjusting nut to increase or decrease the tension. The spring I have shown is an arc shaped spring instead of the coil spring shown in Figs. 1 and 2. This spring will not become clogged by concrete or material.

Other modifications of spring can be used or a compression or pressure instead of tension spring can be substituted, but still be within the scope of my invention in operating discharging gates or blades as described and from either end of the mixer.

It will be readily seen that the operation of my improvement is partly automatic, in

that when the lever is started or thrown so that the tension of the spring is in the desired direction, the spring will throw the discharge blade or gate and hold it until the operator throws the lever over center of tension again. For this reason it is not necessary to have experts to operate the mixer.

What I claim is:

1. A rotary concrete mixer drum provided in its interior with an adjustable material-deflecting element having a limited range of movement, a rocking shaft extending longitudinally of the drum carrying said element and having an operating lever, and spring mechanism connected with the drum and lever adapted to positively hold the lever, shaft and deflecting element when thrown to the limit of movement in either direction, substantially as set forth. 75

2. A rotary concrete mixer drum provided in its interior with an adjustable material-deflecting element having a limited range of movement, a rocking shaft extending longitudinally of the drum carrying said element and having an operating lever, and spring mechanism connected with the drum having an arc-shaped terminal engaging the lever and adapted to positively hold it and the shaft and deflecting element when thrown to the limit of movement in either direction, 95 substantially as set forth. 80

3. A rotary concrete mixer drum provided in its interior with an adjustable material-deflecting element having a limited range of movement, a rocking shaft extending longitudinally of the drum carrying said element and having an operating lever at each end, and spring mechanism connected with the drum and one of said levers adapted to positively hold the levers, shaft and deflecting element when thrown to the limit of movement in either direction, substantially as set forth. 100

4. A rotary concrete mixer drum provided in its interior with an adjustable material-deflecting element having a limited range of movement, a rocking shaft extending longitudinally of the drum carrying said element and having an operating lever at its end, and spring mechanism embodying an arc-shaped portion connected with said lever adapted to exert tension thereon to positively hold the lever, shaft and deflecting element when thrown to the limit of movement in either direction, substantially as set forth. 110 115

5. The combination with the mixing drum and its chute, of a hinged chute cover and a support therefor and spring controlled means for holding the hinged cover either open or closed. 120

6. The combination with the mixing drum and its chute, of a pivotally mounted cover for the chute, a supporting ledge therefor on the chute, and spring controlled means for holding the cover either open or closed. 130

7. The combination with the mixing drum and its chute, of a pivotally mounted cover for the chute, a supporting ledge therefor and a supplemental extensible side projecting 5 from the chute, and spring-controlled means for holding the cover either open or closed.

8. The combination with the mixing drum and its chute, of a hinged chute cover within said drum and a support therefor, and spring 10 controlled means for holding the cover either open or closed.

9. The combination with the mixing drum and its chute, of a rocker shaft extending longitudinally within the drum, a supporting ledge within the chute, and a material-deflecting element mounted on the rocker shaft having a restricted range of movement limited by the supporting ledge, substantially as set forth.

20 10. The combination with the mixing drum and its chute, of a rocker shaft extending longitudinally within the drum, a sup-

porting ledge within the chute, a material-deflecting element mounted on the rocker shaft having a restricted range of movement limited by the supporting ledge, and spring-controlled means for actuating and holding the rocker shaft and deflecting element, substantially as set forth.

11. The combination with the mixing 30 drum and a chute therein having a supporting ledge inside and below the edge of the chute, of a hinged chute cover having a limited range of movement adapted to bear upon said ledge, and spring-controlled means 35 for holding the hinged cover open or closed, substantially as set forth.

In testimony whereof I affix my signature in presence of two witnesses.

MATTHEW HOWARD REED.
